UNITED STATES PATENT OFFICE

FRANK C. HACHENEY, OF VANCOUVER, WASHINGTON

DESIGN FOR A HEADLIGHT

Application filed February 11, 1929. Serial No. 30,014. Term of patent 14 years.

To all whom it may concern:

Be it known that I, FRANK C. HACHENEY, a citizen of the United States, and a resident of the city of Vancouver, county of Clarke, and State of Washington, have invented a new, original, and ornamental Design for Headlights, of which the following is a specification, reference being had to the accompanying drawings, forming part thereof.

Fig. 1 is a front view of a headlight showing my new design;

Fig. 2 is a side view of a headlight embodying this design, the rear of the casing of the headlight being shown in dotted lines as the dominant feature resides in the front portion of the casing.

I claim:

The ornamental design for a headlight, as shown and described.

FRANK C. HACHENEY.
